Charles E. Barr

ATTORNEY

UNITED STATES PATENT OFFICE.

RALPH E. MARBURY, OF WILKINSBURG, PENNSYLVANIA, ASSIGNOR TO WESTINGHOUSE ELECTRIC & MANUFACTURING COMPANY, A CORPORATION OF PENNSYLVANIA.

LIGHTNING ARRESTER.

Application filed April 7, 1922. Serial No. 550,275.

To all whom it may concern:

Be it known that I, RALPH E. MARBURY, a citizen of the United States, and a resident of Wilkinsburg, in the county of Allegheny and State of Pennsylvania, have invented a new and useful Improvement in Lightning Arresters, of which the following is a specification.

My invention relates to protective devices, 10 more especially to a protective device employed in conjunction with condensers to protect them from abnormal voltages.

It is among the objects of this invention to provide a protective device for condensers 15 which shall be designed to break down at voltages that are in excess of the normal voltages for which the condenser is designed and which shall function to protect other devices included in the same circuit.

20 It is another object of this invention to provide a device of the above designated type which shall be of simple compact structure, which shall be inexpensive and adapted to be readily manufactured in production 25 quantities and which shall be readily accessible for renewals in case of breakdown in service.

Condensers employed in electric railways are connected between the line and the 30 ground and are ordinarily designed for approximately double the normal voltage. Occasionally, abnormal charges accumulate for a very short time which breaks down the insulation of the condenser and leaves the 35 electrical apparatus unprotected until repaired.

My invention provides means for protecting the condenser element so that its operative function is undisturbed in the event 40 of accumulation of excessive line voltage.

In the accompanying drawing, constituting a part hereof and in which like reference characters designate like parts,

Figure 1 is a diagrammatic view of a condenser electrically connected between line 45 and ground having a protective device connected therewith in accordance with this invention;

Fig. 2 is a cross-sectional view, partially in elevation, of a casing embodying a condenser and a protective device;

Fig. 3 is a side elevational view of a special type of gap plug constituting one of the embodiments of this invention; and

Figs. 4 and 5 are plan and cross-sectional views, respectively, of the plug elements employed in the protective device.

Referring to Fig. 1, a condenser 1 is connected between a line 2 and ground, 3, and a protective device, comprising a gap element or plug 4 and a series resistance rod 5, is shunted across the condenser 1 at the points 6 and 7. The plug 4 (Figs. 4 and 5) comprises a pair of sheet-metal discs 8 and 9 having a dielectric 10, preferably of a thin film of varnished silk therebetween to provide a film cut out or gap.

Referring to the Fig. 2, the condenser 1 is disposed within a suitable casing 11 having terminal bushings 12 mounted therein 70 and connected to the terminals 13 of the condenser. The plug 4 is inserted through the condenser casing and is provided with a pair of spring clips 14 making contact with a pair of strips 15 connected to the terminals 75 12 through the resistance rod 5. The elements 8, 9 and 10 are inserted between the spring clips 14 to insure contact under pressure, thereby completing the shunt connection across the terminals 12. A lamp 16 is 80 shunted across part of the resistance 5 to indicate the operative condition of the protective device.

The operation of the device is briefly as follows: The condenser 1 is connected to the 85 terminals 12 in a manner indicated in the Fig. 2, with protective and resistance elements 4 and 5, respectively, shunted across the terminals.

The resistance plug 4 and rod 5 is of such 90 magnitude that the current will pass from one terminal through the condenser to the other terminal under normal conditions. On small switching surges, which occur frequently, the main condenser 1 is designed to 95 protect the apparatus. If a sudden ab-

normal voltage accumulates on the line 2, causing a violent surge, the current will pass through the resistance 5 across the contacts 15 to the plug 4 and will break down the film cut-out consisting of the varnished silk film 10 between the metal discs 8 and 9, causing them to weld or fuse together, and short-circuiting the condenser 1.

Practically all the current in the circuit 10 passes through the rod 5, thus notifying the operator that the plug 4 is short-circuited. The circuit is then broken by removing the trolley from the line and the plug 4 is then removed and replaced by a similar plug 15 having a new film element therein to again render the device operative. The lamp 16, upon short-circuiting of the plug 4, becomes lighted, owing to the current flowing through rod 5, thus providing additional means for 20 notifying the operator of failure of the plug device.

It will be readily understood from the above description of my invention that a protective device formed in accordance 25 therewith provides a simple and inexpensive means for protecting condensers employed in trolley-line service. This device is relatively inexpensive, as compared with condensers, having sufficient insulation to withstand abnormally high voltages that may 30 occur in service.

Although I have described a specific embodiment of my invention, it will be obvious to those skilled in the art that various 35 changes may be made in the details of construction thereof. For instance, the condensers and housing may be of any other suitable shape and construction, the plug may be of any suitable construction to hold conducting 40 and dielectric materials and may be connected in any suitable manner to the resistance and terminal elements. The lamp connected in the resistance circuit is not essential and may be eliminated. These and other 45 changes may be made in the details of construction of my invention without departing from the principles herein set forth.

I claim as my invention:

1. The combination with an electric line 50 exposed to excess voltage surges and apparatus connected to said line, of an excess-voltage protective device therefor comprising a condenser connected to said line, said condenser being of such capacity as to limit the voltage rise across said apparatus on 55 normal switching surges or the like to a value below the breakdown voltage of the condenser insulation, and a shunt circuit including a film cut-out and a current limiting device connected in parallel to said condenser, said cut-out being proportioned to break down when the voltage across the condenser rises above a safe operating value.

2. In combination with a condenser, a 60 protective device comprising a removable

film-cut-out element and a resistance element in series, said elements being shunt-connected across said condenser.

3. The combination with an electric line 65 exposed to excess voltage surges and apparatus connected to said line, of an excess-voltage protective device therefor comprising a condenser connected to said line, said condenser being of such capacity as to limit the voltage rise across said apparatus on 70 normal switching surges or the like to a value below the breakdown voltages of the condenser insulation, a shunt circuit including a film cutout and a current limiting device connected in parallel to said condenser, said cutout being proportioned to break 75 down and become short circuited at voltages corresponding to the breakdown voltage of said condenser, and an annunciator responsive to a flow of current in said shunt circuit. 80

4. An excess-voltage protective device comprising a condenser to be connected across the protected apparatus and means connected in parallel to said condenser for preventing a rise of voltage across the condenser terminals above a value corresponding to the breakdown voltage of the condenser insulation, said means comprising a gap-device and a current limiting resistor connected in series, said gap device being 90 proportioned to break down below the breakdown voltage of said condenser and to establish a permanent current path in shunt to said condenser, and means for indicating the flow of current in said shunt path. 100

5. In combination with a condenser, a protective device comprising a plurality of metal discs having a layer of varnished silk therebetween and a resistance element in series therewith, said discs and resistance 105 element being shunt-connected across said condenser.

6. In a protective device, a container having a condenser disposed therein and connected to terminals thereon and a protective device consisting of a film cutout and a resistance element, said cutout and resistance being shunt-connected across said terminals. 110

7. In a protective device, a container having a condenser disposed therein and connected to terminals thereon, a plug having a plurality of metal discs and a strip of insulating material therebetween, a pair of spring clips, said plug being held between said clips, and a resistance element making contact with one of said clips, said element and plug being connected across said terminals. 115

8. In a protective device, a container having a condenser disposed therein and connected to terminals thereon, a renewable plug having a plurality of metal discs and a strip of varnished silk therebetween, and a pair of spring clips, said plug being held between said clips, a resistance element mak- 120

ing contact with one of said clips and said element and plug being connected across said terminals.

9. In a protective device, a container having a condenser disposed therein and connected to terminals thereon, a renewable plug having a plurality of metal discs and a strip of varnished silk therebetween, a pair of spring clips, said plug being held

between said clips, a resistance element making contact with one of said clips and an electric-light bulb connected across a portion of said element, said element and plug being connected across said terminals. 10

In testimony whereof, I have hereunto 15
subscribed my name this 31st day of March,
1922.

RALPH E. MARBURY.
